INVENTOR,

James F. Davis

UNITED STATES PATENT OFFICE.

JAMES F. DAVIS, OF FALL RIVER, MASSACHUSETTS.

GUN-SWAB.

SPECIFICATION forming part of Letters Patent No. 268,004, dated November 28, 1882.

Application filed July 3, 1882. (No model.)

To all whom it may concern:

Be it known that I, JAMES F. DAVIS, of Fall River, in the county of Bristol and State of Massachusetts, have invented a new and useful Improvement in Gun-Cleaners.

The object of my invention is the simultaneous expansion and contraction of both the swabs on the gun-cleaner at exactly the same time to precisely the same size or circumference, with but one operation for all.

The following is a specification of my invention, reference being had to the accompanying drawings.

Like letters indicate like parts.

Figure 1 is a sectional view of my gun-cleaner and invention shown in the gun-barrel. Fig. 2 is a side view of my invention.

C is a solid cylinder with a small bore and perforations, *a a*, substantially like the cylinder C set forth in my Letters Patent No. 247,541, bearing date September 27, 1881, except that in my present invention the nut on the end of cylinder C is a rigid head, I.

B is a tubular joint, also substantially the same.

E E are the swabs, and E' E' the metal disks inclosing the same.

A is a movable sleeve or hollow cylinder over the solid cylinder C, moving back and forth freely when acted upon from *x x*, but prevented from turning by the pin *c* in the solid cylinder C projecting through the slot *b* in the sleeve or hollow cylinder A. If preferred, this sleeve or hollow cylinder can be constructed of a spiral spring of suitable power.

e e are perforations in the hollow cylinder A, to allow the passage of the cleaning-fluids from tube B through the bore and perforations *a a* in solid cylinder C.

x x is a screw-joint, with which tube B and solid cylinder C are united.

In my present invention both swabs E E are acted upon and simultaneously expanded or

contracted to the desired circumference or size, through the sleeve A and the screw *x x*, by 45 simply turning the handle of the gun-cleaner. Tube B, being part thereof, operates at *x x* the screw-joint, and thereby, by means of the sleeve or cylinder A, is tightened against or relieved from pressure at I. A, being between the disks 50 E E' and swabs E E and I and *x x*, acts reciprocally, and the swabs are simultaneously acted upon on both sides, and equally expanded or allowed to contract as the pressure is brought to bear or relieved from *x x*.

Heretofore to expand or contract the swabs it was necessary to first tighten the nut on the one end of the solid cylinder C and then tighten at the handle on the other end. It is obvious that it was almost an impossibility to adjust 60 both the swabs to the gun-barrel nicely and exactly of the same size—a thing much sought for and greatly needed. By my combination with sleeve A the difficulty of unequal pressure and unequal sizes is overcome and removed, 65 because by means of my sleeve A the pressure acts exactly at the same instant with equal force upon all sides of the disks and swabs.

What I claim as a novel and useful invention, and desire to secure by Letters Patent, 70 is—

In a gun-cleaner, the disks E E' and the expandable swabs E E, held between said disks, in combination with the perforated cylinder C, having at one end a fixed head, I, and at the 75 other end a screw-thread, *x*, together with the sleeve A, engaging with said cylinder C by means of the slot *b* and pin *c*, and having perforations *e e* to discharge the cleansing-fluid from the duct *a* between said swabs E E, substantially as and for the purpose specified.

JAMES F. DAVIS.
